CLAIM

(62) Division of application No. 29/281,455, filed on Jun. 22, 2007, now Pat. No. Des. 572,664.

We claim the ornamental design for a lighting control keypad, as shown and described.

(51) **LOC (9) Cl.** **13-03**

DESCRIPTION

(52) **U.S. Cl.** **D13/164**

FIG. 1 is a perspective view of a lighting control keypad according to a first embodiment of our new design.

(58) **Field of Classification Search** ..... D13/162, D13/164, 169, 170, 171; D10/108, 116, D10/118; D8/353; 200/5 A, 293, 296, 297, 200/329, 333, 335, 339, 341, 520, 530, 552; 220/241; 307/125, 139; 315/291-296

FIG. 2 is a front view thereof.

See application file for complete search history.

FIG. 3 is a left side view thereof.

FIG. 4 is a right side view thereof.

FIG. 5 is a top view thereof.

FIG. 6 is a bottom view thereof.

(56) **References Cited**

FIG. 7 is a perspective view of a lighting control keypad according to a second embodiment of our new design; and,

U.S. PATENT DOCUMENTS

FIG. 8 is a front view thereof, the left side, right side, top, and bottom views, respectively, of the second embodiment being identical to the left side, right side, top, and bottom views of the first embodiment.

The rear views form no part of the design and are omitted. The portions of the drawings appearing in broken line are for environment only and do not form a part of the claimed design.
